UNITED STATES PATENT OFFICE.

HAROLD W. SHONNARD, OF MONTCLAIR, NEW JERSEY, ASSIGNOR TO ELEVATOR SUPPLIES COMPANY, INC., A CORPORATION OF NEW JERSEY.

DOOR-OPERATING MECHANISM.

Application filed September 5, 1924. Serial No. 736,030.

This invention relates to door operating mechanisms and more particularly to mechanisms of this character especially adapted for use in connection with the doors of elevator hatchways.

In a mechanism of this character it has been customary to employ means to close the door which ordinarily comprises a spring which is effective throughout the door closing movement. In such door closing movements there is almost always a considerable inertia to be overcome before the door begins to close rapidly. This is often the case even when the first portion of the closing movement of the door is assisted manually, inasmuch as elevator operators ordinarily have to close hundreds of hatchway doors a day and therefore exert the minimum effort which is necessary to start the door closing movement. Moreover it is usually not practicable to increase the strength of the door closing spring or other means sufficiently to overcome the inertia of the door, since this spring or other means is usually compressed or otherwise rendered operative by the spring movement of the door, which movement will be opposed and retarded by any extraordinary strength of the door closing means. Time of operation is, of course, a most essential element to be considered in connection with elevator installations in the busy office buildings of the present day, and the time lost while the usual door closing means is overcoming the inertia of the door is, in the aggregate, very likely to be enough to necessitate the installation of an extra elevator, with the consequent heavy addition to the cost, not only of installation, but also of operation and overhead. In any case, the cost of operation and the quality of the service given is very dependent upon the operation of the elevator with as much speed as possible. In this connection it should be noted that with a view of obtaining complete safety of operation many elevators are equipped with means which prevent their movement as long as the hatchway doors are open.

It is therefore one object of this invention to provide in a door operating mechanism means to accelerate the initial portion of a door closing movement.

The door closing spring is usually arranged to be operative upon a rod or other movable member, such as the stem of a

plunger of a door closer and check mechanism, and the rod is pivotally connected to a door operating lever. The pivotal connection between the rod and the lever ordinarily has consisted of a shaft carried by the lever and running through a transverse bore in the rod. This type of connection has proved somewhat unsatisfactory because the wear of the shaft against its bearing necessitates the replacement of the rod periodically during the use of the mechanism, and when the rod is connected to the plunger of a door check mechanism, which is difficult to take apart and to reassemble, the replacement of the rod will entail considerable time and expense.

It is therefore another object of the invention to provide an improved connection between the relatively movable members of a door operating mechanism whereby this and other disadvantages of the connections at present in use may be overcome.

The invention will be described in its preferred form in connection with a particular type of door operating mechanism such as is shown in the accompanying drawings, in which—

Fig. 1 is a view of an elevator hatchway showing the doors and the door operating mechanism;

Fig. 2 is a view partly in section showing the door closer and check mechanism;

Fig. 3 is an enlarged section on the lines 3—3 in Fig. 2 showing the pivotal joint between the plunger stem and the door operating lever; and

Fig. 4 is a section on the line 4—4 in Fig. 3.

The particular embodiment of the invention to be described is shown in the drawings as applied to a pair of horizontally sliding doors 10 and 11 which are adapted to close a hatchway to an elevator shaft. The mechanism for opening and closing the doors comprises a door operating lever 12 consisting of members 14, 15 and 16. The member 14 is pivoted to the door 10 at 17 and pivotally joined to member 15 at 18. Member 15 is pivoted on door 11 at 19, and is pivotally connected at 20 to member 16 which is pivoted at 21 to the side of the elevator hatchway. On the end of lever member 15 adjacent to the pivotal connection 18 there is provided a grip 23 to facilitate a manual operation of the lever.

Fig. 2 illustrates a particular type of door closing and check mechanism which embodies the invention in its preferred form and which is adapted for use with a door operating lever such as just described. This mechanism comprises a casing 25 which is pivotally attached at 26 to a bracket 27 fastened to the side of the elevator hatchway. In the casing 25 are formed a dash pot cylinder 28 and a spring containing chamber 29 which may be of any well known type.

In the dash pot chamber 28 there is provided a plunger 31, the stem of which consists of a rod 32 which extends through the chamber 29 and outwardly through the cap 43 toward the door operating lever 12. The stem 32 is pivotally connected to an attachment 34 on member 16 of this lever. As shown in the drawings this pivotal connection comprises a connecting member 36 which is detachably mounted on the end of the rod 32 in any suitable manner, as by means of a pin 37 which is held in place by a nut 38. A shaft 40 extending through the attachment 34 and the connecting member 36 and running transversely to the stem 32 serves to connect members 34 and 36 so as to provide the desired pivotal joint. This shaft may be held in place by any suitable means, as by cotter pins 41, which permit its easy removal when the wear of the shaft on the connecting member 36 necessitates the replacement of either of these members. In the particular type of mechanism shown in the drawings, the door-closing means consists of a spring 42 which is spiraled about the stem 32 inside chamber 29 and which is compressibly held between a cap 43 at the top of casing 25 and a cap 44 which is carried on the rod 32. The spring 42 is thus adapted to be compressed as the doors 10 and 11 are opened, and to be effective to push the rod 32 downwardly and to cause a movement of the lever 12 whereby the door is closed. In order to accelerate the initial portion of this door-closing movement and to assist the spring 42 in overcoming the inertia of the door, there is provided means which is effective at the beginning of the door-closing movement and which in mechanism shown in the drawing consists of a spring 46 which is spiraled about the stem 32 and rests upon the cap 44. On the opposite end of the spring 46 there is set a slidable washer 47 which is adapted to contact with the cap 43 toward the end of the movement of the stem 32 as the doors are opened so that the spring 46 will be compressed between cap 43 and cap 44 at the end of this movement.

It is believed that the operation of the particular mechanism shown in the drawings, will be readily apparent from the foregoing description. As an elevator is

stopped opposite a closed hatchway such as is shown in Fig. 1, the operator will seize the grip 23 and pull it downwardly, as the mechanism appears in the drawing, so as to fold the lever 12 and to pull the doors 10 and 11 open, or to the left as shown in Fig. 1. As the lever 12 is folded the member 16 will be moved upwardly so as to rotate about its pivot 21, and will draw the stem 32 in an upward direction, which movement will carry the cap 44 toward the top of the casing 25. During the first part of this opening movement, when the inertia of the doors is to be overcome, only the spring 42 will be compressed. Towards the end of its movement, however, the cap 44 causes also a compression of spring 46; so that when the doors 10 and 11 are in their completely open position, and the members of the toggle lever are folded completely upon each other, the plunger 31 will be toward the top of the dash pot chamber 28, the cap 44 will be near the top of the chamber 29, and both the springs 42 and 46 will be compressed. It should be noted that the spring 46 serves as a cushion for the doors at the end of their closing movement.

When he desires to close the doors of this type the operator releases them, whereupon the pressure of the springs 42 and 46 will be effective upon the bent lever 12 to cause the movement of the doors toward their closed position. The auxiliary spring 46 will add sufficient force to the pressure exerted by spring 42 at the beginning of this movement to readily overcome the inertia of the doors, and to greatly accelerate their movement. After the doors are once moving rapidly toward their closed position, the pressure alone of the spring 42 against the cap 44 will be sufficient to carry on their movement. It has been found that by the use of an auxiliary door-closing means such as spring 46, the time of closing of a door can be reduced one-half.

When, in the course of time, the pin 40 and its bearing in connecting member 36 become worn through constant operation of the doors, either of these members may be readily replaced by the removal of the shaft from its bearings after the removal of pin 41 and by detaching member 36 from stem 32 after the removal of the nut 38 and the pin 37. It should also be noted that the provision of the connecting member 36 enables the shaft 40 to be made as large as the rod 36, as shown in the drawings, or larger than the rod, if desirable. Moreover the particular type of connection shown in the drawings is especially compact and may be used even when space requirements have little room between the shaft 40 and the cap 43 when the door is closed.

While a specific form of the invention has been described in connection with particular

mechanism it should be clearly understood that the invention is limited neither to the form or embodiment shown and described, but is capable of being employed in numerous forms and in a large variety of embodiments.

What is claimed is:

A driving connection comprising a yoke member, a one piece rigid connecting member having a socket therein and an opening above said socket, a shaft pivotally mounting said connecting member between the arms of the yoke member, said shaft passing through the opening in the connecting member and through the yoke member, said

connecting member having a passage intercepting the socket of the connecting member, a driving rod having one end received in the socket, and means for taking up wear between said rod and socket wall, said means comprising a passage in said rod aligned with the socket intercepting passage in the connecting member, a taper pin passing through the aligned passages of the driving rod and the connecting member, and positive means for securing said taper pin in different positions of adjustment.

Signed at Hoboken, N. J. this 3rd day of September 1924.

HAROLD W. SHONNARD.
